DESIGN FOR AN AUTOMOTIVE SIGNAL LENS

Ray F. Stoddard, Dayton, Ohio

Application December 24, 1936, Serial No. 66,741

Term of patent 7 years

To all whom it may concern:

Be it known that I, Ray F. Stoddard, a citizen of the United States, residing in the city of Dayton, in the county of Montgomery and State of Ohio, have invented a new, original, and ornamental Design for an Automotive Signal Lens, of which the following is a specification, reference being had to the accompanying drawing forming part hereof.

The figure is a perspective view of an automotive signal lens, showing my new design. The opposite side of the design is plain.

I claim:

The ornamental design for an automotive signal lens, as shown and described.

RAY F. STODDARD.
